SHOE AND THE METHOD OF MAKING
THE SAME

John J. Walsh, St. Louis, Mo.

Application June 18, 1947, Serial No. 755,526

9 Claims. (Cl. 36—16)

1

This invention relates in general to certain new and useful improvements in shoes and the method of making the same.

It is the principal object of the present invention to provide a new and unique method of making shoes and, more particularly, women's shoes, which method is simple, economical, and makes possible the achievement of a comfortably fitting shoe of highly attractive, novel design or appearance.

It is also an object of the present invention to provide a novel method of making a soft-soled shoe which has the casual style and appearance of a slip-lasted shoe, and is extremely flexible on the foot of the wearer.

It is an additional object of the present invention to provide a shoe of novel design and appearance which is long-wearing and exceptionally comfortable on the foot of the wearer.

With the above and other objects in view, my invention resides in the novel features of form, construction, arrangement, and combination of parts presently described and pointed out in the claims.

In the accompanying drawings (two sheets)—

Figure 1 is a perspective view of a midsole having a heel-wedge applied thereto as the first step in the shoe-making method of the present invention;

Figures 2, 3, 4, and 5 are plan views or so-called "pattern views" of the component parts for making a preferred form of shoe in accordance with the method of the present invention;

Figure 6 is a perspective view of the upper of a shoe made in accordance with the method of the present invention;

Figure 7 is a perspective view of the assembled upper and outer sole;

Figure 8 is a perspective view of the underside midsole showing the area thereof which is coated with adhesive;

Figure 9 is a side elevational view of a completely assembled shoe partly broken away to show the interior construction thereof;

Figure 10 is a fragmentary sectional view taken along line 10—10 of Figure 9;

Figure 11 is a perspective view of the assembled upper in position over the last;

Figure 12 is a fragmentary sectional view taken along line 12—12 of Figure 11 showing schematically the process of binding up the marginal edges of the outer sole;

Figure 13 is a perspective view of the shoe after removal from the last;

Figure 14 is a perspective view of the shoe il-

2

lustrating the final operation of inserting the so-called sock-lining, the view being partly broken away to show more clearly the internal construction; and

5 Figure 15 is a transverse sectional view taken along line 15—15 of Figure 13.

In broadest outline, the method of the present invention comprises the stitching together of a plurality of suitably patterned upper parts or 10 sections to form a combined upper and soft outer sole, and cementing in place a flexible insole. The assembled upper, outer sole, and insole is then placed on a last and rolled or bent up so that the seam line between the upper and outer 15 sole is elevated about the region of contact with the ground or floor when the shoe is being worn. The heel-margin of the outer sole is provided with a pinked flap portion which is then pulled over and cemented down on the inside face of the insole and the shoe is finally finished by inserting and cementing a sock-lining upon the inside face of the insole and pulled-over flap portion or heel-margin of the outer sole.

Referring now in more detail and by reference 20 characters to the drawings, 1 designates a flexible insole provided upon its under face with a heel-wedge 2 formed preferably of cork or other similar material, as shown in Figure 1. A soft sole member or outer sole 3 is stamped out of a suitable section of leather in the form shown in Figure 2 and is provided around its heel periphery with an arcuate flange or flap 4. The upper is formed of a heel strip 5 and two companion-shaped upper sections 6, 7, as shown in Figures 3, 4, and 6.

25 The upper sections 6, 7, are exact opposites or "mirror images," so to speak, and are each provided with vamp sections 8 and instep sections 9 having slits 22 for accommodating a buckle-strap (not shown) in the finished shoe. It should be noted that the upper sections 6, 7, are curved outwardly in the region of their toe portions, as at 10, between match-marks 11, 11', to accommodate the pointed toe flap portion 12 30 of the sole member 3. The upper section 6 is preferably, though not necessarily, provided with a guide-mark 13 for indicating the position of the buckle (not shown) and, similarly, the upper section 7 is provided with a guide-mark 14 for indicating the proper position of the secured end of the strap (also not shown).

35 The upper sections are finally provided with integral heel-strap portions 15 and are stitched together at such heel strap sections 15 and out-seamed along the margins of the instep sections 9.

and vamp sections 8 down to the marks 11 so as to present a smooth interior against the instep of the wearer's foot. The heel strip 5 is then stitched flatwise over the seam between the ends of the heel-strap 15 and short sections or strips of fabric tape *t* are stitched upon the inner faces of the upper sections 6, 7, and along the lower margins thereof, in the region of the shank, in the formation of a completed upper 16, as shown in Figure 6. The outseaming is continued, joining the toe flap portion 12 of the sole member into the gap between the curved portions 10 of the upper sections 6, 7, and such stitching continued to join the side margins of the sole member 3 to the side margins of the upper sections 6, 7, as shown in Figure 7. The insole 1 and its heel-wedge 2 are adhesively secured in place, the fore-part of the inside face of sole member 3 being freshly coated with adhesive so that the insole 1 can be slid around slightly and thereby aligned, whereupon the heel parts are then pressed together to secure the members together. It should be noted that the sole member 3 is substantially wider than the insole 1, as best seen in Figure 10.

The assembled upper 16 and sole member 3 are then placed on the last 17, as shown in Figure 11, and the margins of the sole member 3 rolled up by a hand tool H, as at 18, as shown in Figure 12, thus lifting the seam-line between the upper 16 and the sole member 3 substantially above the zone of wearing contact with the ground, street, or floor, when on the foot of the wearer. Upon removal from the last 17, a band of adhesive is applied to the upper face of the insole 1, around the periphery of the heel and shank, and to the exposed or inside faces of the flap 4 and tape strips *t*. Thereupon, the flap 4 and tape strips *t* are pulled inwardly and pressed down in place, as shown in Figures 13 and 15, the tape strips *t* serving to draw in and hold the shank portions of the upper sections 6, 7, to give the finished shoe a snug-fitting shank. Finally, a sock lining 19 is cemented in place, as shown in Figure 14, to complete the shoe S.

It should be understood that changes and modifications in the form, construction, arrangement, and combination of the several parts of the shoe and in the method of making the same may be made and substituted for those herein shown and described without departing from the nature and principle of my invention.

Having thus described my invention, what I claim and desire to secure by Letters Patent is:

1. A shoe comprising an upper having its peripheral margin in the region of its toe-part extending inwardly and upwardly in the provision of a notch-like line of separation, a soft outer sole stitched to the peripheral margins of the upper, said sole having a toe-flap shaped to conform to the notch-like line of separation of the upper and a heel-flap extending peripherally outwardly around the heel portion of the sole member, said toe-flap being stitched to the upper along the margins of the notch-like line of separation, and a flexible inner sole member disposed within the upper and secured upon the inner face of the sole, said heel-flap being folded over and secured upon the upper face of the inner sole member around the heel periphery thereof.

2. A shoe comprising an upper, a flexible insole, a flexible soft outsole, the latter being similar in shape to but larger than the insole around a substantial portion of its periphery and being bent upwardly around the edges of the insole, and tape-like means secured upon the inner face of the

upper in the region of the shank of the shoe, said tape-like means being secured to the insole.

3. A shoe comprising an upper, a flexible insole, a soft outsole, the latter being similar in shape to but larger than the insole around a substantial portion of its periphery and being bent upwardly around the edges of the insole, and tape-like means secured upon the inner face of the upper in the region of the shank of the shoe, said tape-like means extending flatwise over the margins of and being secured to the insole.

4. The method of making a shoe comprising the following steps: providing an upper, marginally stitching the upper to a soft outsole, providing a flexible insole similar in shape to but smaller than the outsole, setting the insole within the shoe upon the outsole, and bending up the marginal portions of the outsole to lift the seam between the outsole and upper above the plane of the normal walking surface when the shoe is being worn.

5. The method of making a shoe comprising the following steps: providing an upper, marginally stitching the upper to a soft outsole, providing a flexible insole similar in shape to but smaller than the outsole, setting the insole within the shoe upon the outsole, and rolling the marginal portions of the outsole and thereby bending up the marginal portions of the outsole to lift the seam between the outsole and upper above the plane of the normal walking surface when the shoe is being worn.

6. The method of making a shoe comprising the following steps: providing an upper, providing a flexible insole, providing a soft outsole, the latter being similar in shape to but larger than the insole around a substantial portion of its periphery and being provided around its heel periphery with a projecting flap, marginally stitching the upper and outsole together, placing the insole within the shoe upon the inner face of the outsole, placing the shoe on a last with the flap projecting outwardly, upwardly deforming the outsole, removing the last, and folding over and securing the flap to the insole.

7. A shoe comprising an upper having outwardly curved portions in the region of the toe part thereof, a soft outsole stitched to the lower margins of the upper and having a toe flap extending between the curved portions of the upper, said outsole having a heel flap, and a flexible insole member disposed within the upper and secured upon the inner face of the soft outsole with the heel flap of said soft outsole secured upon the upper face of the insole member.

8. A shoe comprising an upper, a flexible insole, a soft outsole larger than the insole and having a projecting flap provided around its periphery, said soft sole being bent upwardly around the edges of the insole with the projecting flap secured upon the inner face of the insole, and tape-like means secured upon the inner face of the upper in the region of the shank of the shoe, said tape-like means extending flatwise over the margins of, and being secured to, the insole.

9. A shoe comprising an upper, having outwardly curved portions in the region of the toe part thereof, a soft sole stitched to the lower margin of the upper, said sole having a toe flap extending between the curved portions of the upper and being stitched to the inner margins of said curved portions, said soft sole being further provided with a heel flap extending peripherally outwardly around the heel portion of the sole, a

flexible insole disposed within the upper and secured upon the inner face of the sole, said heel flap being folded over and secured upon the upper face of the insole around the heel periphery thereof and tape-like means secured upon the inner face of the upper in the region of the shank of the shoe, said tape-like means extending flatwise over the margins of, and being secured to, the insole.
